UNITED STATES PATENT OFFICE.

DE WITT TAYLOR LYON, OF CHICAGO, ILLINOIS, ASSIGNOR OF ONE-HALF TO BABET.
R. H. LYON, OF CHICAGO, ILLINOIS.

VENTILATING DEVICE.

Application filed August 15, 1924. Serial No. 732,288.

To all whom it may concern:

Be it known that I, DE WITT TAYLOR LYON, a citizen of the United States, and a resident of Chicago, county of Cook, and State of Illinois, have invented a new and useful Improvement in Ventilating Devices, of which the following is a full, clear, and exact description.

My invention relates to improvements in ventilating devices, and it consists in the combinations, constructions, and arrangements herein described and claimed.

An object of my invention is to provide an adjustable ventilator of the so-called mushroom type but which is an improvement over that set forth in my prior United States Patent No. 1,425,028 of August 8, 1922.

The device which forms the subject of the present application is designed like that of the prior patent aforesaid to be used primarily in connection with theatre ventilation, the device being disposed underneath the seats of the theatre.

An object of the present invention is to provide a ventilator which has a greater ventilating opening than that set forth in my prior patent, but at the same time may be placed on, and will operate effectively on a platform or tier of no greater width than that occupied by the device set forth in the patent. In other words, the present invention is designed to afford greater facility for ventilation without taking up a correspondingly greater space.

A further object of my invention is to provide a ventilator of an oblong shape which has means for permitting the adjustment of the device to permit more or less air to enter.

A further object of my invention is to provide a ventilating device of the type described having relatively few parts, and being provided with means for adjustment which render such adjustment comparatively easy.

Other objects and advantages will appear in the following specification, and the novel features of the invention will be particularly pointed out in the appended claims.

My invention is illustrated in the accompanying drawings, forming part of this application, in which—

Figure 1 is a top plan view of the device,
55 Figure 2 is a section along the line 2—2

of Figure 1, looking in the direction of the arrows, and

Figure 3 is an end view of the device.

In carrying out my invention I provide an oblong hollow casting 1, substantially of elliptical form having rounded end portions. This casting forms a wall and has an integral flange 2 near the bottom thereof arranged to rest on the floor 3, the latter being provided with an opening 4 for the admission of the lower portion of the casting 1. Extending ears or lugs 5 are provided for securing the casting to the floor, these ears or lugs being provided with suitable openings for screws or bolts.

On the exterior of the casting 1 is a series of integral finger-like ridges 6, separated by spaces 7. The spaces 7 it will be observed are closed at one end by an integral connecting member 8 from which the fingers 6 extend laterally. I preferably make use of two sets of fingers 6 one at each end of the device, as shown in the drawing. I also provide between the two sets of fingers 6 ridges 9, separated by the spaces 10, the ridges 9 being in horizontal registration with the fingers 6 and the spaces 10 being in horizontal registration with the spaces 7.

The top portion of the ventilator is shown at 11. It will be observed that it consists of a cover having a dished or concave-shape. The cover extends over the edge of the casting 1 and is turned down slightly. It is provided with integral legs or supports 12 which have ribs 13 on their inner sides, 90 these ribs being separated by spaces 14.

The rounded end portions of the casting are made on arcs having their centers at the intersection of the major and minor axes of the device.

From the foregoing description of the various parts of the device, the operation thereof may be readily understood. It has been found in the ventilation of large buildings, such as theatres or the like, that to secure the best results, frequent adjustment of the ventilator is desirable. The present device fulfills the requirements of a ventilator which is easily adjustable. Consider Figure 3 of the drawing. Here a ventilator is shown open. If it is desired to partially close it, the cover portion 11 is rotated until the ridges 13 which are supported by the ridges 6 and 9 pass beyond the ends of these ridges, when the cover may be lowered bod-

ily until the ridges 13 engage the next longer ridge 6, when the rotation of the device can be reversed so as to bring the cover into its normal position, but now resting on a ridge 8 which is lower, i. e., nearer the floor. This will of course tend to partially close the opening between the cover and the upper end of the casting. Similarly the cover may be lowered so that its supports will rest on any of the ridges 6, these, as shown in the drawing, being successively longer toward the bottom.

The purpose of having the lower ridges successively longer is so that the ridges on the legs may be brought into instant registration. If the ridges 6 were all of the same length, the cover would drop down to the bottom when it had cleared the upper ridges 6. Where each ridge is progressively longer, it drops down onto the next ridge and is in immediate registration with the ridges on the exterior of the device at this level.

In the construction described, the threading of the main casting which was necessary in the device shown in the prior patent is obviated. A greater area for ventilation is secured with a given width, which width need only be the minor dimension of the device. After the desired position is reached, the cover may be locked in position by means of the set screw 15 so as to prevent accidental displacement.

I claim:

1. A ventilating device comprising an oblong wall of substantially elliptical shape, a plurality of supporting members carried by said wall on the exterior thereof, said members being progressively longer from top to bottom of said wall, and a cover portion having legs arranged to fit over said wall

and provided with means for engaging any of said supporting members for holding said cover in predetermined relation with respect to the top of the wall.

2. A ventilating device comprising an oblong hollow casting having rounded ends, a series of parallel ridges disposed on the outside of the casting, said ridges being progressively longer toward the bottom of the device, a cover, and supports for said cover having means arranged to rest on any of said ridges for supporting said cover at predetermined positions with respect to the top edge of the casting.

3. A ventilating device comprising an elongated hollow casting of substantially elliptical shape having a series of integral parallel ridges, said ridges being progressively longer from top to bottom of the casting, a cover having a plurality of legs, each of said legs being provided with ridges arranged to engage the ridges of said cover and being shiftable to engage other ridges, whereby the cover may be supported at varying distances from the top of the casting.

4. A ventilating device comprising an elongated hollow casting of substantially elliptical shape having a series of integral parallel ridges, said ridges being progressively longer from top to bottom of the casting, a cover having a plurality of legs, each of said legs being provided with ridges arranged to engage the ridges of said cover and being shiftable to engage other ridges, whereby the cover may be supported at varying distances from the top of the casting, and means for locking the cover in its shifted position.

DE WITT TAYLOR LYON.
